United States Patent Office.

A BRAM P. ANTHONY, OF MORRISON, ILLINOIS.

Letters Patent No. 65,152, dated May 28, 1867.

IMPROVED CLOTHES-DRYER ATTACHMENT FOR STOVE PIPES.

The Schedule referred to in these Letters Patent and making part of the same.

TO ALL WHOM IT MAY CONCERN:

Be it known that I, A. P. ANTHONY, of Morrison, in the county of Whitesides, and State of Illinois, have invented a new and useful improvement in Clothes-Dryers; and I do hereby declare that the following is a full, clear, and exact description of the same, reference being had to the annexed drawings, making part of this specification, in which—

Figure 1 is a perspective view.

Figure 2 is an elevation.

The same letters are employed in both figures in the indication of the same parts.

My invention consists in the application of an adjustable framework to the pipe of a stove, upon which clothes, &c., may be hung to be dried by the heat of the pipe.

A is a stove pipe; B a wire or rod, the ends of which are bent to encircle the pipe. The parts are brought together, or nearly so, and carried upward along the pipe, being bent into divergent loops, B¹, and again carried upward a little distance, and then bent respectively so as nearly to encircle the pipe, when they are curved outwardly so as to form the ring B², surrounding the pipe, on which it is intended that the articles to be dried shall be suspended, exposed to the heat of the stove and pipe. A ring, C, is passed through the loops B¹. It has a diameter sufficient, when it is at the upper end of the loops, as shown, where they approach most nearly to one another, to allow the separation of the parts sufficiently to allow the dryer to be put upon the pipe. When the ring is turned downward, its inner surface pressing upon the outside of loops which are divergent, forces together the ends and clamps the dryer upon the pipe. When the ring is turned entirely down it is caught by the swell of the loops and held in place.

What I claim as my invention, and desire to secure by Letters Patent, is—

The wire B, forming a ring, B², and loops B¹, in combination with the ring C, by means of which it may be clamped upon a stove pipe, substantially as and for the purpose set forth.

In testimony whereof I have signed my name to this specification in the presence of two subscribing witnesses.

ABRAM P. ANTHONY.
